UNITED STATES PATENT OFFICE.

ELMER W. EATON, OF NASHUA, NEW HAMPSHIRE.

SUITCASE-HOLDER FOR AUTOMOBILES.

1,267,750.

Specification of Letters Patent. Patented May 28, 1918.

Application filed December 1, 1917. Serial No. 204,869.

To all whom it may concern:

- Be it known that I, ELMER W. EATON, a citizen of the United States, residing at Nashua, in the county of Hillsborough and 5 State of New Hampshire, have invented certain new and useful Improvements in Suitcase-Holders for Automobiles, of which the following is a specification, reference being had to the accompanying drawings.
- 10 This invention relates to means for holding suit cases or like containers on the running boards of automobiles, and the general object of the invention is to provide a device of this character which is very simple, 15 which may be cheaply made and which is extremely effective for the purpose intended.
- A further object is to provide a device of this character which is of such construction that it may be conveniently carried and 20 which is extremely compact, and in this connection to provide a device which is adaptable to carrying any number of suit cases and holding these suit cases firmly in place upon the running board.
- 25 Other objects will appear in the course of the following description.

My invention is illustrated in the accompanying drawings, wherein:—

Figure 1 is a side elevation of an automobile provided with my improved attachment;

Fig. 2 is a top plan view of the suit case with my attachment arranged to hold the case in place;

Fig. 3 is a longitudinal section on an enlarged scale, taken on the line 3—3 of Fig. 2; and

Fig. 4 is a perspective view of a portion of the running board showing the manner 40 in which the straps are connected to the running board.

Referring to these drawings, it will be seen that my improved construction comprises a plurality of brackets or yokes 10, 45 which are each formed with eyes at its ends through which screws 11 may pass, the middle portion of each bracket or yoke being deflected outward for engagement with a strap 12. There are preferably four of these 50 straps, one for each of the yokes or brackets, and the lower ends of the straps 12, as illustrated in Fig. 4, extend downward around the deflected portions of the brackets and then extend upward and are returned upon 55 themselves through a transverse band 13. By this means, the straps may be lengthened

or shortened. I do not wish to be limited, however, to this particular means of attaching the straps 12 to the yokes or brackets.

Coating with the straps 12 is a circular 60 disk 14 which is preferably of leather having a diameter nearly equal to the width of a suit case and to this disk 14 there is attached a plurality of short strap sections 15 carrying buckles 16. The straps 12 pass 65 through these buckles 16. Preferably the strap sections 15 are riveted to the leather disk 14, as illustrated in Fig. 3. I do not wish to be limited to any particular means for attaching the strap sections 15 to the 70 disk 14, however.

As illustrated in Fig. 2, the brackets or 75 yokes 10 are arranged in approximately rectangular relation and the strap sections 15, when the device is applied, extend at right angles to each other, two of the strap sections extending parallel to the running board and the other two at right angles to the running board. This, however, is a preferable arrangement. The brackets or yokes 80 10 may be arranged at any desired distance from each other, so that the holder may accommodate one or more suit cases or like containers. The suit cases may be either 85 set up on end or disposed in the usual manner upon the running board and the straps 12 may be taken up initially in the manner heretofore described and as shown in Fig. 4, and then the straps tightened by passing them through the buckles 16 until the suit 90 case is firmly held in place upon the running board. It will be obvious that the straps 12 may be readily disconnected from the brackets 10 and that when so disconnected the holding device may be folded up into 95 very small compass and placed within the car. The brackets or yokes 10 will project 100 above the running board only a very slight distance. Many running boards are perforated and in this case the brackets 10 may be held in place by bolts passing through the eyes of the brackets and through the perforations of the running board and by this means the yokes or brackets may be readily 105 adjusted nearer to or farther from each other to accommodate parcels or cases of different sizes.

The circular leather disk 14 will not scratch or otherwise mar the suit case or other parcel with which it engages and there 110 will be no strain on the suit case itself which would tend to rack it. The device is very

simple, can be easily applied, may be very cheaply made and, as before remarked, will fold up into small space for carriage when out of use. It will be noted from the drawing that the brackets are so arranged that one of the brackets projects out from the edge of the running board, two of the brackets are disposed transversely of the running board where they will not offer any obstruction to the feet and the other bracket is disposed longitudinally of the running board but adjacent the inner margin thereof, so that when the disk 14 with its stops is removed from engagement with the brackets, the running board is left practically unobstructed.

Having described my invention what I claim is:—

The combination with the running board of an automobile, of means for holding suit

cases thereon comprising brackets attached in quadrilateral relation and having medially disposed deflected portions, a disk of relatively flexible material adapted to be disposed on top of the case and having a plurality of radially disposed strap sections, buckles attached to said strap sections, and a plurality of straps engaged with said buckles and extending downward to the brackets, each of said straps at its lower end being passed beneath a bracket, then upwardly extended, the end of said strap being then detachably engaged with the body of the strap.

In testimony whereof I hereunto affix my signature in the presence of two witnesses.

ELMER W. EATON.
